UNITED STATES PATENT OFFICE.

RALPH R. LAPOINTE, OF HUDSON, MASSACHUSETTS, ASSIGNOR OF ONE-HALF TO
BENJAMIN F. LEVY, OF BOSTON, MASSACHUSETTS.

BROACH-OPERATING MECHANISM.

1,362,536.

Specification of Letters Patent. Patented Dec. 14, 1920.

Application filed December 13, 1918. Serial No. 266,645.

To all whom it may concern:

Be it known that I, RALPH R. LAPOINTE, a citizen of the United States, and resident of Hudson, county of Middlesex, Commonwealth of Massachusetts, have invented an Improvement in Broach-Operating Mechanisms, of which the following description, in connection with the accompanying drawings, is a specification, like characters on the drawings representing like parts in each of the several views.

This invention relates to broaching machines and particularly to machines of the horizontal draw-cut type. More especially the invention has to do with a machine of this type wherein the broach draw head is operated by a plurality of screws spaced apart at opposite sides of the broach holding socket so that the operative pull in the broaching operation is equally and evenly distributed between the screws, and so that the broach head moves evenly and freely on its ways without tendency to binding or undue friction. One important object of the invention is to provide improved operating mechanism for such plurality of screws that is simple, strong, and reliable in action and capable of easy and convenient control. A further object is to provide improved and simplified operating gearing that is capable of use either with stationary operating screws or with rotary screws. The foregoing and other objects and advantages of the invention will more fully appear from the following detailed description, and the distinctive features of novelty will be pointed out in the appended claims.

Referring to the drawings:

Figure 1 is a side elevation of a machine constructed in accordance with our invention, an intermediate portion being broken away;

Fig. 2 is a lengthwise vertical section approximately on line 2—2 of Fig. 3;

Fig. 3 is a horizontal section on line 3—3 of Fig. 1;

Fig. 4 is a transverse vertical section on line 4—4 of Fig. 3; and

Fig. 5 is a horizontal section of the rear portion of the machine showing a modified form wherein the screws are not rotated.

The bed frame 10 of the machine extends horizontally, having at its forward end a vertical face 11 to which the work holding face plate is adjustably secured, and having at its rear an enlarged housing 12 in which the operating gearing is mounted. Intermediate its length the bed frame is equipped with horizontally extending guide ways at its sides which may be in the form of rails 13 for supporting and guiding a draw head 14 for its sliding operative movement. The draw head 14 has a passage 15 centrally therethrough to receive a broach holder 16 to which is secured the tang of the broach B, this holder being as shown held in place by interengagement with a suitable threaded and headed bushing 17 fitted in said passage. Engaged with the draw head 14 at each side of the broach holding socket provided by the passage 15, are operating screws 18, 18^a, these being spaced equally at each side of the socket 15 and in a common plane therewith so that the operative pull on the broach will be evenly distributed between said screws. The screws 18, 18^a as shown in Fig. 3 are engaged with nut bushings 19 fixed in the draw head. The outer ends of the screws are reduced as seen at 20 and have bearings in bushing sleeves 21 fitted in the forward end of the base frame, these bushings being as shown as large as the full diameter of the screws so that upon removal of said bushings the screws may be removed through the passages therefor. The inner portions of the screws are formed as plain shafts 22, 22^a fitted in bearings of a thickened web 23 extending transversely at an intermediate rear portion of the bed. The screw shafts are shouldered as indicated at 24 just in front of the transverse web 23 and have fitted thereon thrust collars 25 with interposed anti-friction bearings 26 between said collars and bearing faces at the front of the web 23. The screw shaft portions 22, 22^a extend through the web 23 into the gear housing 12 where they have keyed thereon driving gears 27, 27^a, the ends of the shafts having enlarged heads 28 which are fitted into recessed seats 29 of said gears. The engagement of the heads 28 with the gears 27, 27^a constitutes means for receiving

and taking up the operative thrusts on the screws and interposed between said gears and the web 23 are anti-friction bearings 30. As will be seen from Figs. 2 and 3 the gear 27 is mounted behind the gear 27^a so that these gears can overlap. This permits the gears 27, 27^a to be of adequate size for the purpose required and also permits driving engagement with both these gears by an elongated pinion 31 which is fast on a clutch sleeve 32 rotatably and slidably mounted on a shaft 33 fixed at its ends in the machine frame. Thus the gears 27, 27^a are both rotated in the same direction and the screws 18, 18^a will hence be of the same pitch. For a purpose that will presently appear the teeth of the pinion 31, and also of the gears 27, 27^a meshing therewith, are preferably inclined or spiral as shown in Figs. 2 and 3. Rotatably fitted on the shaft 33 at one side of the clutch sleeve 32, *i. e.*, to the left as seen in Fig. 2 is a clutch head 34, the hub of which has keyed thereto a spur gear 35 which is in driven engagement with a pinion 36 fast on a shaft 37 mounted for rotation and limited sliding movement in bearings of the machine base. The shaft 37 also has keyed thereon, but so that it can slide therethrough, a pinion 38 in driving engagement through an intermediate gear 39 with a gear 40 loosely mounted on the shaft 33 and having a clutch face 41 on its inner side engageable by the clutch face at the outer end of the clutch sleeve 32. The shaft 37 extends without the machine base where it has keyed thereon a flaring disk 42 equipped with a friction face 43 engageable by a conical clutch seat in a prime driving wheel 44 loosely mounted on a bushing 45 encircling the shaft 37 and extending outward from a sleeve of the machine base. The clutch face 43 is normally held in operative engagement with the drive wheel 44 by a compression spring 46 mounted on the shaft 37 and reacting against a collar 47 fixed thereon. The shaft 37 may be moved endwise to disengage said friction clutch members by a swinging arm 48 fixed to a shaft 49 journaled transversely in the base, and when the shaft 37 is thus shifted to the right as seen in Fig. 2, the flaring disk 42 after disengaging the wheel 44 is pressed against a brake surface 50 yieldingly pressed inward toward the same by spring mountings 51. The clutch sleeve 32 is operated by a swinging arm 52 fixed on a shaft 53 journaled transversely in the machine frame. The shaft 53 has fixed thereto a horizontally extending arm 54 equipped at its outer end with a pin 55 engaging in a cam slot 56 of a bar 57 guided for horizontal sliding movement at one side of the machine frame. The bar 57 also controls the swinging of the arm 48 which governs the engagement of the friction clutch 43, for this purpose having a second cam slot 58 engaging a pin 59 on the outer end of an arm 60 which is fixed to the shaft 49. The inner end of the bar 57 has pivoted thereto the lower end of a lever 61 which is fulcrumed to the machine bed at 62 and has its upper end equipped with gear teeth making a segment operating connection 63 with the lower end of a lever 64 pivoted to the bed at 65, the upper end of which is pivotally connected to the inner end of a rod 66 extending horizontally and slidably guided at one side of the machine bed near the top thereof. The bar 66 has engaged therewith by a pin and slot connection 67 near its outer end a hand lever 68 pivoted to the bed at 69. The bar 66 also has depending therefrom near its inner end a lug 70 engageable with a lug 71 carried by the draw head 14 and projecting out through a slot 72 of the bed. It may now be understood that at the completion of an operative movement of the draw head 14, *i. e.*, at its limit of inward movement the lug 69 will engage the lug 68 shifting the bar 66 and hence the cam bar 57. It will be noted that the outline of the cam slot 58 is such that at the beginning of the sliding movement of the bar 57 to the right as shown in Fig. 1, the pin 59 will begin to travel downward, thus shifting the shaft 37 endwise at once, throwing out the driving clutch 43 and applying the brake 50. As this takes place the pin 55 is moving along a neutral part of the slot 56 so that the clutch sleeve 32 is not shifted until after the prime power clutch 43 is disengaged and the shaft 37 stopped. It will be noted that upon the stoppage of the shaft 37 and hence of the clutch head 34, the tendency to further forward movement by momentum of the screws with their gears 27, 27^a, will itself tend to throw the clutch sleeve 32 out of engagement with the clutch head 34 both by reason of the inclined backs of the co-operative clutch teeth and also by reason of the inclined or spiral formation of the teeth of the pinion 31 and the gears 27, 27^a meshing therewith. To insure the complete throwing of the clutch sleeve 32 to a neutral position, however, and also to reverse it, the pin 55 next encounters an active portion of the cam slot 56 as the bar 55 is moved farther to the right whereupon the clutch sleeve 32 is shifted to its limit of movement to the right in Fig. 2 engaging the clutch face 41 of the reverse driving gear 40. In practice the first described movement is usually produced by the automatic stop device including the stop lugs 70, 71, which thus automatically operates to throw out the driving clutch and stop the machine at the end of an operative movement of the draw head. Then the bar 64 being shifted farther to the

right the draw head 14 is returned to initial position by power transmitted through the reverse gear 44.

- It is also practicable to employ the present improved arrangement of driving gears in a form wherein the screws are not rotated and in Fig. 5 I show such a form of the invention. In this figure the draw head 140 has fixedly socketed therein as by cotter pins 10 or the like, the inner ends of the screws 180, 180^a. These screws extend inward through bearing bushings 73 of the transverse backing web 230 of the machine bed. Within the gear housing 120 at the rear of the machine bed are mounted rotary nuts 190 engaging the screws 180, 180^a, these nuts having keyed or otherwise rigid therewith driving gears 270, 270^a set one behind the other in like manner as the gears 27, 27^a, and both driven from a single elongated pinion in like manner as the pinion 31. The nuts 190 which are relatively long have bearings in sleeves 74 rigid with the machine frame housing 12 and at the inner ends of said nuts anti-friction roller bearings 75 are interposed to take the operative thrust against the backing web 230 in like manner as similar anti-friction bearings provided in the first described form. In this form of the invention the screws 180, 180^a, project through the machine housing 12 and outward according to the length of travel required of the draw head. It is to be observed that in both forms of the invention described the driving gearing is simple yet powerful and efficient, and both screws being driven directly from the common driving pinion 31, the screw movements are better synchronized than is the case where one screw is driven from the driving gear of the other screw with the more or less back-lash incident thereto as has heretofore been usual. Further it is to be noted that the positive forward and reverse driving clutches including the clutch faces formed at the ends of the clutch sleeve 32 are thrown into engagement only when the power friction clutch 43 is disengaged and the driving shaft 37 stationary.
- For holding the work in operative position, the vertical front face 11 of the machine bed is equipped with an undercut slab 76 to which is fitted for vertical adjustment a face plate 77, such adjustment being effected by having adjusting screws 78 imbedded on the top and bottom of the face plate, these screws being fitted for adjustment in overhanging flanges of heads 79 bolted or otherwise secured to the slabs 76. The face plate is also preferably equipped with an annular groove 80 on its outer face concentric with the central passage 81 thereof, for the purpose of receiving a centering rib of the work holder to aid in correctly locating the work with reference to the broach. A suitable lubricating system
- is provided including piping 82 with a discharge nozzle 83 delivering lubricant adjacent to and just over the working area of the broach. I am aware that the invention may be embodied in other specific forms as 70 to its several features as set forth without departing from the spirit or essential attributes thereof, and I therefore desire the present embodiment to be considered as illustrative and not restrictive, reference being 75 had to the appended claims rather than to the foregoing description to indicate the scope of the invention.
- Having described my invention, what I claim as new and desire to secure by Letters 80 Patent is:
1. Broach operating mechanism, comprising a broach draw head, spaced apart operating screws therefor each having fixed at its inner end a relatively large driving gear, 85 said gears being offset laterally with respect to each other and overlapping, and driving mechanism including a relatively small elongated pinion engaging both said gears to drive them and operate said screws in 90 unison.
  2. Broach operating mechanism, comprising a broach draw head, spaced apart operating screws therefor engaged therewith, each screw having fixed at its inner end 95 a relatively large driving gear, said gears overlapping and laterally offset with respect to each other, and a relatively small elongated driving pinion engaging both said gears to drive them and operate said screws 100 in unison, said pinion having inclined teeth for the purpose stated.
  3. Broach operating mechanism, comprising a broach draw head, spaced apart operating screws therefor engaged therewith, 105 each screw having fixed at its inner end a relatively large driving gear, said gears overlapping and laterally offset with respect to each other, a relatively small elongated driving pinion engaging both said gears to 110 drive them and operate said screws in unison, and driving mechanism for said pinion including a forward drive connection, a reverse drive connection and a clutch device shiftable to engage either of said connections at will. 115
  4. Broach operating mechanism, comprising a broach draw head, spaced apart operating screws therefor engaged therewith, each screw having fixed at its inner end a 120 relatively large driving gear, said gears overlapping and laterally offset with respect to each other, a relatively small elongated driving pinion engaging both said gears to drive them and operate said screws in unison, and driving mechanism for said pinion including a forward drive connection, a reverse drive connection and a clutch device shiftable to engage either of said connections at will, said clutch device and said elongated 125
  - 130

pinion being formed as a unit and said elongated pinion having inclined teeth for the purpose stated.

5. Broach operating mechanism, comprising a broach draw head, spaced apart operating screws therefor, relatively large actuating gears fixed on the ends of said screws mounted adjacent each other laterally offset

and in overlapping relation, and driving mechanism including a relatively small ¹⁰ elongated pinion engaging both said gears to drive them and operate said screws in unison.

In testimony whereof I have signed my name to this specification.

RALPH R. LAPOINTE.
